DEVICE FOR FEEDING FILAMENTS AND SIMILAR ARTICLES

John Flaws, Jr., Cleveland Heights, Ohio, assignor to General Electric Company, a corporation of New York

Application March 22, 1934, Serial No. 716,813

15 Claims. (Cl. 140—132)

My invention relates to devices for feeding wires, rods, tubes or similar articles and more particularly to the feeding of lengths of such articles one at a time from a pile thereof. My invention is particularly useful for feeding coiled filaments for incandescent lamps. Such filaments are usually quite small and quite flexible so that they have a tendency to pack together in a pile and become very difficult to separate. To facilitate feeding, the filaments are disposed in a pile parallel to one another and are handled as carefully as possible. Even though much care is expended the filaments have a tendency to become entwined and tangled together so that if one is lifted, others often hang thereto. Extreme care must be taken not to bend or injure the filaments particularly as said filaments are usually coated with "getter."

The principal object of my invention is to provide a device for effectively picking up coiled filaments one at a time from a pile thereof. To effect this object, I provide jaws for entering into a pile of filaments and gripping one of said filaments, and means for carrying said jaws to and from said pile. Another object of my invention is to provide means for increasing the probability of said jaws picking up a filament from the pile. In order to do this I prefer to provide one jaw with a plurality of notches or pockets therein, any one of which may engage a filament, and a second jaw which passes across said notches successively until it comes to a notch within which a filament is disposed, said filament being then clamped in said notch, and filaments which may be disposed in succeeding notches remain in the pile upon the subsequent withdrawal of the jaws from said pile. This feature provides continuous feeding at all times and eliminates filament jams in the pile. Another object of my invention is to provide means for feeding a sufficient number of filaments for a long period of operation and to provide a number of piles of said filaments which are automatically brought to the feeding position successively. This object is accomplished by disposing a pile of filaments in each of a plurality of containers mounted on a turret and providing means for indexing said turret. Other objects and features of my invention will appear from the detailed description which follows of a species thereof and from the accompanying drawings. The particular species of my invention described in detail hereafter is designed to be attached to a machine for automatically mounting incandescent lamp filaments such

as that disclosed in Patent 1,907,532—Flaws, issued May 9, 1933.

In the drawings Fig. 1 is a perspective view of my device for feeding incandescent lamp filaments with a portion thereof broken away and carried to one side; Fig. 2 is a perspective view of the turret therefor and its indexing mechanism; Fig. 3 is a vertical elevation partially in section of the device at the feeding position showing the relative location of the various parts; Fig. 4 is a vertical section on an enlarged scale through the filament bucket adjacent the pick-up jaws which are shown at the position of their maximum penetration therein; Fig. 5 is a perspective exploded view of the pick-up jaw assembly; Fig. 6 is a plan view of a turret bucket or container for filaments at feeding position and parts associated therewith; Fig. 7 is a perspective view of a filament bucket modification; and Fig. 8 is a side elevation of the ends of modified filament pick-up jaws.

The embodiment of my invention shown in Figs. 1 and 2 consists of a turret 10 having buckets or containers 11 distributed about the periphery thereof in which the coiled filaments 12 are piled. The filaments lie parallel to each other and tangentially to the turret on the bottoms of the buckets which slope slightly downward toward the middle. The insides of the buckets are highly polished so as to cause the filaments to slide down by their own weight into a pile at the middle of the bottom. As shown in Fig. 1 all the turret buckets except one are enclosed by housing 13 and cover 14 and are heated to keep the filaments free from moisture by heating means such as a pair of lamps (not shown) connected to plugs 15 and 16. Wires 16' furnish the current to said lamps. The housing is attached to slide 17 whereas the turret is rotatably mounted on column 18 extending from said slide. The entire assembly is mounted in substantially a vertical position on bracket 19 which is mounted at each side on posts 20 (only one of which is shown).

The filaments are fed from the exposed bucket into which the jaws 21, 22 and 23 shown in Figs. 3, 4, and 5 penetrate. This movement results from a downward movement of rod 24 to which head 25, which carries said jaws, is attached and which carries the jaws into the pile of filaments, the position of deepest penetration being shown in Fig. 4. The end of jaw 22 is provided with a plurality of notches or pockets 26 each of which may receive a portion of a filament, said notches or pockets preferably comprising partially circu-

lar portions of substantially the same diameter as the filaments. Jaw 22 is fastened directly to the head 25 and carries down with it a few of the filaments, the remainder slipping to either side thereof. The middle portions of the filaments are bent down into the opening 27 in the bucket and often are tilted up slightly at the ends. During the downward movement the jaws 21 and 23, which are disposed adjacent opposite sides of jaw 22, are in the open position as indicated in the dotted lines in Fig. 4. These jaws 21 and 23 are located below washers 28 and 29 which, through bolt 30 and nut 31, clamp them to finger 32. The said bolt 30, carrying the finger 32 and jaws 21, 23, is mounted between the cone points of screws 33 (only one shown) in head 25 and is held in the open position by wedge 35 which prevents spring 36, located between the finger 32 and screw 37 in the head, from pulling it out of position. The wedge 35 is supported on screws 38 which are mounted in holes 38' in opposite sides of the head, and during the open position said wedge is located against the said finger adjacent shoulder 39. Spring 40 extending between the wedge and a post 41 in holes 41' in the head holds it in this position.

The downward movement of the jaws results from movement of rod 24 (Fig. 1) which is actuated by lever 42 acting through links 43, collar 30 44, spring 45 and block 46. The block 46 is fastened directly to rod 24 and keeps the jaws in the correct plane by slidably engaging post 47 in bracket 48. Collar 49, which is fixedly attached to said rod 24, rides against collar 44, which is slidably mounted on said rod, until nuts 50 and 51 strike stop sleeve 52 in bracket 48. As the lever 42 continues to move farther, spring 45 is contracted and the end of screw 53 on said lever strikes the end of collar 54 and rod 55, pushing it downward. This motion causes the jaws 21 and 23 to move across the notches in jaw 22 as the wedge 35 is pushed upward into the position shown in Fig. 3 by lever 56, permitting spring 36 to pivot said jaws 21, 23 clockwise. Lever 56 is turned about pin 57 in bracket 48 by rod 55 which is connected thereto by yoke 58. Spring 59 (Fig. 1) carries the rod back into position after the operation has been completed. Lever 42 operates about a pin 60 in bracket 48 and is actuated from the face of a cam 61 located on a shaft 62. The said lever 42 is operated through link 63 by rod 64 which connects through link 65 and its fittings 66 and 67 to lever 68 on shaft 69. The lever 68 turns about the shaft 69 which is held in a bracket 70 extending between supporting posts 20 and is turned by lever 71 through spring 72 which extends between arm 73 on lever 68, and a post lever 71. Lever 71 is turned by track 74 in cam 61 which is engaged by roller 75 on a pin in the end of said lever.

As jaws 21 and 23 move across jaw 22 (counter-clockwise in Fig. 4) the ends thereof, which extend beyond the end of jaw 22, sweep the filaments below said jaw 22 back until they engage a filament in one of the notches 26 of the jaw 22 which is then firmly clamped in said notch. It will be apparent that when three notches are provided in jaw 22, there will be three chances of picking up a filament in one operation of the jaws. The line of movement of said jaws 21, 23 passes through the said notches, that is, portions of said jaws move substantially longitudinally of the notched lateral end portion of jaw 22 and successively across the edges of said notches, so that if a filament is disposed in the first notch,

it will be gripped therein by the jaws 21, 23 which then cannot move any farther, so that only one filament will be picked up at a time. The said notches 26 are also preferably spaced apart a distance less than the diameter of the filaments to provide greater assurance that the uppermost filaments in the pile will be engaged in the said notch. The said jaws, with a filament gripped therebetween at its mid-point, are now moved upward into the position shown in Fig. 3, thus pulling the mid-portion of said filament through slits 78, 79 (Fig. 6) formed between the front edge of a plate 76 and fingers 93, 94 mounted at the said front edge of plate 76. This action is positive all through the operating mechanism as collar 44 then lies against collar 49 and arm 80 of lever 71 moves lever 68 by engaging with the end of bolt 81 therein. At this position, a pair of needles 77 (one of which is shown), disposed in lines passing along each side of the jaws, above plate 76 and at an angle to the horizontal, are moved down into the position shown in Fig. 3, between the mid-portion of the filament and said plate 76. Each of said needles is embedded in an end of a rod 82 which rides in arm 83 extending from pin 84 (Fig. 1) of bracket 48, and are caused to move into this position by the lever 85, the flange of which strikes the end of said rod 82. This motion is against the action of spring 84' which is located between arm 83 and collar 85', and results from a vertical movement of sleeve 86 extending through the central column 18 of the device. The said sleeve 86 engages lever 85 through pin 87 which operates through an opening in column 18. Lever 85 operates about screws 88 in a collar 88' attached fixedly to said column 18 and is actuated by lever 89 which connects to sleeve 86 through links 89' and collar 90 attached to the bottom end thereof. Lever 89 is operated about a pin 91 in bracket 70 through engagement of a roller 92 on an arm thereof with the edge of cam 61. The needles 77 are then caused to move apart laterally to engage the outer portions of the gripped filament and pull them through the slits 78, 79 which are just large enough to allow one filament to pass through, thus combing said gripped filament free from other filaments below said slits which may have adhered thereto. Any adhering filaments then drop back into the bucket 11. The needles 77 are operated by further movement of lever 85, the flange of which comes in contact with rollers 95 on pins 96 in lugs 97 of arms 83 which swing against the resistance of spring 97' located between spring posts in both of the arms 83 and which carry the arms from a position set by stop screw 98 contacting with arm 99 of bracket 48. Plate 76 is mounted on cross bar 100 (Fig. 3) which rests on cover plate 101 on bracket 103 which in turn may be mounted on a mounting machine (not shown) such as the one hereinbefore referred to. Each finger 93 and 94 is welded to an end of a spring plate 104, the other end of which is attached to block 105 by screws 106 and 107 (Fig. 6) and which can be moved with respect to the plate 76 to adjust the size of the slots 78, 79 by adjusting screw 108. Block 105 is attached to guide plate 109 which is fixedly mounted on bracket 103.

The jaws, 22 and 21, 23, with a single filament held therein, are carried farther upward until wedge 35 strikes the end of pin 110 (Fig. 1), at which time the filament touches fingers 109' and 110'. The fingers stop the filament from vibrating. Pin 110 is resiliently mounted on a

spring (not shown) in arm 111 and moves the wedge down against shoulder 39 on finger 32 (Fig. 3), thereby opening the jaws. The filament is released, falls onto plate 76, and thence by gravity travels down the sloping surface thereof to slide 112 between cross bar 100 and guide plate 109. Guides 113 and 114 are provided to prevent the filament from shifting as it falls and to keep foreign matter out. Fingers 109' and 110' are clipped to the guides which are mounted on bar 100. Slide 112 is pulled back to deposit the filament on slide 441 (which corresponds to gate 441 of the mounting machine disclosed in the Flaws patent hereinbefore referred to). As 15 the slide 112 is drawn back the filament is lowered on the fingers 115 of plate 109 and fingers 116 of slide 112 which mesh together and which deposit said filament on slide 441 in a straight and untwisted condition at the proper location. 20 The slide 112 rides on bracket 103 beneath plate 101 and is moved by lever 117 (Figs. 1 and 3) which engages an aperture in said slide through roller 118. Lever 117 turns with pin 120 which is mounted on arm 121 extending from bracket 25 103 and is turned by arm 122. When the slide is in the closed position, spring 123, which is located between arm 122 and a post in bracket 103, holds said arm in the proper position but when the slide is actuated, the arm is moved by roller 30 124 on lever 68 which strikes rod 125 mounted in said arm 122.

Means are provided for indexing the turret to present successive buckets 11 at the feeding position, although such means may be disconnected if desired. The indexing action jars the filaments in the containers or buckets 11 down into position so as to settle the loose ones in place. This means is shown in Figs. 1 and 2 and operates from lever 68 through universal joint 126 and rod 127. The rod is connected to arm 128 through universal joint 128 which turns freely about column 18 and engages, through pawl 130, a ratchet 131 on a vertical sleeve portion 132 of the turret 10. The pawl 45 130 turns about pin 133 and is kept against the ratchet by spring 134 which extends between a post in the pawl and another post 135 in arm 128. When it is desired to have the turret remain in one position the pawl is shifted so that protuberance 136 thereon rests against post 135. The ratchet is coupled to the turret by pin 137 and is provided with another set of teeth 138 which are engaged by a roller 139 to properly position the turret. The said roller 139 is mounted on pin 140 in a lever 141 which is mounted on pin 142 in bracket 143 and which is drawn against the ratchet by a spring 144. Bracket 143 is fixedly attached to column 18 and supports post 145 to which spring 144 is attached 50 as well as a brake which prevents the turret from over running. The brake consists of band 146 which is fastened to post 145, is wrapped about a smooth part of the ratchet, and is attached to rod 147 passing through said post 145. 55 Tension is applied to the band by spring 148 located about said rod between the post and nuts 149 threaded on said rod. Increased tension in the brake band causes the roller 139 to snap into position more abruptly, thus jarring the turret more to cause the filaments to settle better.

The particular buckets and jaws described may be supplanted by others shown in Figs. 7 and 8 which are particularly suitable for feeding larger 75 filaments. The bucket 150 differs from the

bucket 11 in that one half of the bottom thereof has a larger opening 151 therein and the other half has a smaller opening 152 and two tongues 153 and 154 extending along the plane of said half into the opening 151 in the other half. The filament 12 lies as before across these openings, but is supported in this instance by spring wires 155 and 156 which are fastened to the back end of the bucket and fit loosely in holes in the front end. The spring wires are provided as a "cushion" bottom, to support the filaments in the larger opening 151 which is used to prevent the larger filaments from being distorted, which might happen with a small opening such as that in buckets 11. The jaws differ in that jaw 22, 15 the stationary jaw, has a plurality of vanes 157 extending therefrom which form notches or pockets substantially equal in width to the diameter of the filament coil and jaws 21' and 23', 20 the movable jaws, are provided with notches 158 therein for registering with the filament pocketed in jaw 22'.

I do not wish to be limited strictly to the constructions described herein since various modifications may of course be made, such as the 25 elimination of one of the jaws 12 or 23 or the provision of two jaws such as the jaw 22 with notches therein and a single jaw like 21 or 23 disposed therebetween.

What I claim as new and desire to secure 30 by Letters Patent of the United States, is:

1. In a device for feeding articles of the class described, the combination of a container for said articles, a pile of said articles being disposed therein substantially parallel to one another, a pair of jaws, means for moving said jaws into engagement with said pile of articles, one of said jaws having a plurality of notches therein each adapted to receive one of said articles, the second jaw being disposed adjacent to said first 40 mentioned jaw and movable relative thereto across said notches therein to engage an article disposed in one of said notches, said article obstructing the further movement of said jaw, and means for withdrawing said jaws from said pile 45 of articles.

2. In a device for feeding articles of the class described, a jaw having a plurality of notches in an edge thereof each adapted to receive one of said articles, and a second jaw disposed adjacent 50 the side of said first-mentioned jaw and mounted so as to be movable relative thereto substantially longitudinally of said notched edge thereof, said parts being so constructed and arranged that said second-mentioned jaw moves success- 55ively across the edges of said notches to engage an article in one of said notches, said article obstructing the further movement of said jaw and being thereby clamped in said notch.

3. In a device for feeding articles of the class 60 described, a jaw having a plurality of notches therein each adapted to receive one of said articles, and a second jaw disposed adjacent the side of said first-mentioned jaw and mounted so as to be movable relative thereto across the edges 65 of said notches, said second-mentioned jaw also having a notch therein at the point where it passes across the notches in said first-mentioned jaw, said parts being so constructed and arranged that said second-mentioned jaw engages an 70 article in one of said notches, said article obstructing the further movement of said jaw and being thereby clamped in said notch.

4. In a device for feeding articles of the class 75 described, the combination of a container for

said articles, a pile of said articles being disposed therein substantially parallel to one another, a pair of jaws, means for moving said jaws into engagement with said pile of articles, 5 one of said jaws having a plurality of notches therein spaced apart a distance less than the diameter of said articles each adapted to receive one of said articles, the second jaw being disposed adjacent to said first mentioned jaw and 10 movable relative thereto across said notches therein to engage an article disposed in one of said notches, said article obstructing the further movement of said jaw, and means for withdrawing said jaws from said pile of articles.

15 5. In a feeding device of the class described, a pair of scissor jaws, one of said jaws having a lateral end portion having a plurality of notches therein and the other jaw being mounted so as to extend beyond said lateral end portion and 20 move successively across the edges of said notches.

6. In a device for feeding articles of the class described, the combination of a container for said articles, a pile of said articles being disposed 25 therein substantially parallel to one another, a pair of jaws, means for moving said jaws into engagement with said pile of articles, one of said jaws having a plurality of notches in the end thereof each adapted to receive one of said 30 articles, the second jaw being disposed adjacent to said first mentioned jaw and movable relative thereto across said notches therein to engage an article disposed in one of said notches, said article obstructing the further movement of said 35 jaw, and means for withdrawing said jaws from said pile of articles.

7. In a device for feeding articles of the class described, the combination of a container for said articles, a pile of said articles being disposed 40 therein substantially horizontally, a pair of jaws disposed above said container, means for lowering said jaws into engagement with said pile of articles, one of said jaws having a plurality of notches in the bottom thereof each adapted to 45 receive one of said articles, the second jaw being disposed adjacent to said first mentioned jaw and movable relative thereto across said notches therein to engage an article disposed in one of said notches, said article obstructing the further 50 movement of said jaw, and means for withdrawing said jaws from said pile of articles.

8. In a device for feeding articles of the class described, the combination of a container for said articles having an aperture in a portion of 55 the bottom thereof, a pile of said articles being disposed therein substantially parallel to one another, a pair of jaws, means for moving said jaws into said pile of articles to the aperture in said container, one of said jaws, having a plurality of notches therein each adapted to receive one of said articles, the second jaw being disposed adjacent to said first mentioned jaw and movable relative thereto across said notches therein to engage an article disposed in one of 60 said notches, said article obstructing the further movement of said jaw, and means for withdrawing said jaws from said pile of articles.

9. In a device for feeding articles of the class described, the combination of a container for 70 said articles having an aperture in a portion of the bottom thereof and spring means disposed across said aperture to form a resilient bottom for a pile of said articles being disposed therein substantially parallel to one another, a pair of 75 jaws, means for moving said jaws into said pile

of articles to the aperture in said container, one of said jaws having a plurality of notches therein each adapted to receive one of said articles, the second jaw being disposed adjacent to said first mentioned jaw and movable relative thereto across said notches therein to engage an article disposed in one of said notches, said article obstructing the further movement of said jaw, and means for withdrawing said jaws from said pile of articles.

10 10. In a device of the class described, a jaw having a plurality of notches therein and a pair of cooperating jaws disposed adjacent opposite sides of said first jaw and movable relative thereto across said notches.

15 11. In a device for feeding articles of the class described, the combination of a turret, a plurality of containers for said articles mounted on said turret, a pair of jaws, means for causing said jaws to advance toward one of said containers to grip one of said articles therein and to retract therefrom, means for causing said jaws to open and release said article, and means for indexing said turret intermittently in proper time relation to the feeding operation of said jaws.

20 12. In a device for feeding articles of the class described, the combination of a container in which said articles are disposed horizontally in a pile, a pair of jaws, means for lowering said jaws toward said container to grip one of said articles therein substantially at the middle and to retract therefrom, a plate disposed above said container having an opening therein to allow passage of said jaws therethrough and horizontal slits extending from opposite sides of said opening, said slits being large enough to permit but 25 one of said articles to pass therethrough.

30 13. In a device for feeding filaments, the combination of a container in which said filaments are disposed horizontally in a pile, a pair of jaws, means for lowering said jaws toward said container to grip one of said filaments substantially at the middle and to retract therefrom, a pair of fingers disposed above said container, means for moving said fingers to a position below said 35 jaws, and means for spreading said fingers apart horizontally to disengage the ends of the filament gripped by said jaws from other filaments which may be adhering thereto.

35 14. In a device for feeding filaments, the combination of a container in which said filaments are disposed horizontally in a pile, a pair of jaws, means for lowering said jaws toward said container to grip one of said filaments therein substantially at the middle and to retract therefrom, a plate disposed above said container having an opening therein to allow passage of said jaws therethrough and horizontal slits extending from opposite sides of said opening, said slits being large enough to permit but one of said filaments 40 to pass therethrough, a pair of fingers disposed above said plate, means for moving said fingers to a position below said jaws, and means for spreading said fingers apart horizontally to pull the ends of the filament gripped by said jaws 45 through said slits to disengage the ends of the filament from other filaments which may be adhering thereto.

45 15. In a device for feeding articles of the class described, an inclined surface upon which 50 said articles are dropped, a horizontally disposed slide, the end of said slide being located adjacent the lower edge of said inclined surface and projecting a short distance therebeyond to receive the article which slides down said sur- 55

face and having fingers depending therefrom, said fingers being inclined in the same general direction as said inclined surface, a plate having an inclination opposite to that of said inclined surface and said fingers, said plate being disposed adjacent to the end of said slide and terminating in fingers extending therebelow and meshing with the fingers on said slide, means for

retracting said slide from said plate to cause the article deposited on the end thereof to slide down between the inner surfaces of said fingers, and a horizontal surface upon which said article is deposited as it passes down between the opened 5 ends of said fingers.

JOHN FLAWS, JR.
